To all whom it may concern:

Be it known that I, Robert L. Mitchell, a citizen of the United States of America, residing at Los Angeles, in the county of Los Angeles, State of California, have invented a new, original, and ornamental Design for a Floor Mat, of which the following is a specification, reference being had to the accompanying drawing, forming a part thereof.

Figure 1 is a top plan view of a floor mat showing my new design, it being understood that the quarter shown is continued throughout the rest of the enclosed area;

Figure 2 is an elevational view of the mat shown in Figure 1;

Figure 3 is an enlarged fragmentary plan view thereof; and

Figure 4 is an elevational section taken along the line 4-4 of Figure 3.

I claim:

The ornamental design for a floor mat, as shown and described.
